UNITED STATES PATENT OFFICE

FOSTER J. HULL, OF HAGERSTOWN, MARYLAND, ASSIGNOR TO PANGBORN CORPORATION,
OF HAGERSTOWN, MARYLAND, A CORPORATION OF MARYLAND

SAND BLAST NOZZLE WIGGLER

Application filed August 18, 1928. Serial No. 300,417.

The invention relates to sand blast apparatus of the type in which a stream of abrasive propelled by air under pressure is projected from a nozzle against the surface to be treated or abraded, which is most commonly, in the apparatus to which the invention relates, the surface or surfaces of castings which are being cleaned by the abrasive stream.

10 In the practice to which the invention particularly relates the nozzle or a group of nozzles is given a reciprocating motion, being ordinarily swung or oscillated with a slow reciprocating arcuate motion, and while 15 the work, which for convenience will be assumed to be castings being cleaned, may be stationary, the castings are ordinarily moved slowly through the area covered by the abrasive stream, the most convenient apparatus 20 being a large rotary table, known as a sand blast table, which rotates with a slow motion carrying the castings through a chamber which overlies and encloses the work supporting surface of the table on one side of the 25 center of rotation of the table. The chamber, in turn, encloses the nozzle or nozzles and the entire area covered by the abrasive stream or streams.

The nozzles are ordinarily oscillated on 30 an arc, the cord of which is located substantially on a radius of the table, the exact path of the nozzles being, however, more or less immaterial so long as it carries the nozzles toward and from the center of the table.

35 A sand blast table of this general type equipped with the swinging nozzles referred to and particularly adapted for use in cleaning castings, is illustrated in my prior Patent No. 1,713,965.

40 The nozzles are ordinarily directed downwardly and the sand blast stream or abrasive stream takes the form of a cone or cones, the apex of each cone being at the nozzle.

45 A difficulty encountered in treating castings and other work in this way results from the fact that under some conditions, particularly where the work is high, i. e., extends upwardly from the table to a point in the vicinity of the nozzle and, therefore, intersects the conical stream where the cone is of

small diameter, narrow paths or channels appear on the surface of the work resulting from the concentration of the abrasive stream or streams on a small area of the surface being treated. The motion of the nozzle combined with the motion of the table passes this small abraded area or areas over the surface of the work, forming the paths referred to. 55

The object of the invention is to overcome this difficulty by spreading and enlarging the cones, which makes the paths referred to much less distinct even where the work approaches close to the nozzles, and substantially equalizes the entire area. 60

The spreading or enlargement of the cones and equalization of the abrasive action throughout the area covered by the abrasive stream from a group of nozzles or a single nozzle, is accomplished by imparting to the nozzle or group of nozzles, in addition to the 65 slow reciprocating motion which, in the form of the machine shown, is an oscillation or swinging on an arcuate path, a secondary reciprocating motion which is in the nature of a vibration in that it is repeated many times 70 for each primary reciprocation or oscillation. 75

This secondary motion is also preferably a reciprocating motion and it has come to be known in the art, so far as it is known and so used, as a wiggle, the mechanism for imparting this motion being termed a wiggler. 80

In the accompanying drawings I have illustrated a machine embodying the features of my invention in the preferred form. I 85 have also shown a modified or secondary form of the invention which illustrates the application of the same principle in a slightly different form. 90

In the drawings:

Figure 1 is a top plan view of a sand blast table equipped with a group of nozzles and means for swinging the nozzles and also means for imparting a secondary motion to them, the motor support and gear casing being removed. 95

Figure 2 is a side elevation of the nozzles and a portion of the nozzle arm adjacent the nozzles, the inner end of the arm being broken away. 100

Figure 3 is an elevation showing the inner end of the nozzle arm with the means for imparting a secondary motion to the nozzles, the broken lines in Figure 2 at the left and in Figure 3 at the right being identical so that the two figures constitute an elevation of the entire arm and mechanism imparting the secondary motion to the nozzles.

10 Figure 4 is a top plan view of the outer end of the group of nozzles and the nozzle arm, the portion of these parts shown in Figure 4 being identical with that shown in elevation in Figure 2.

15 Figure 5 is a top plan view of the inner end of the arm and the actuating mechanism for imparting the secondary motion, the break where the arm is severed in Figures 4 and 5 being identically placed so that the

20 two figures constitute a plan of the entire arm and secondary motion apparatus.

25 Figure 6 is a diagrammatic view illustrating the effect of the secondary motion on the abrasive stream showing the nozzle in full lines in the center position of the secondary motion and showing the same nozzle in dotted lines at each end of the secondary traverse, the stream in the three positions being also illustrated in a corresponding manner.

30 Figure 7 is a vertical section through the nozzle arm at the swinging end where the nozzles are supported, the same being taken on the line 7—7 of Figure 4, the same showing the nozzle supports and pipes in elevation, the ends being broken away.

35 Figure 8 is a view corresponding to Figure 7 showing a single nozzle with the adjacent portion of the pipe and support, the nozzle being shown in central vertical section. This view may be treated as taken on the line 8—8 of Figure 4.

40 Figure 9 is an elevation showing the pivotally mounted end of the rocker arm, including a fragment of the lower end of the eccentric shaft and the eccentric pin.

45 Figure 10 shows the eccentric shaft in section on the line 10—10 of Figure 9 looking down on the same fragment of rocker arm.

50 Figure 11 is a section on the line 11—11 of Figure 10, showing the end of the eccentric shaft, also the eccentric pin and bearing and the eccentric slot in the rocker arm, the eccentric being, however, rotated from the position in which it is shown in Figure 10.

55 Figure 12 is a top plan view corresponding to Figure 5 showing a modified form of the mechanism for imparting the secondary motion to the nozzles. This figure, however, includes a somewhat greater area than is covered by Figure 5.

60 Figure 13 is a section on the line 13—13 of Figure 4.

65 Referring to the drawings by numerals, each of which is used to indicate the same or

similar parts in the different figures, the machine shown in a general way in top plan in Figure 1 and to which the invention has been applied, though it is capable of more general application, comprises a rotary table 1 which is shown as of circular outline. This table is supported on suitable bearings, not shown, and driven in rotation in a horizontal plane about a central axis in any suitable manner, as by means of a motor 2 on a stationary frame 13. This motor drives a worm gear 3 on a shaft 4 at the top of the machine, which shaft drives a second shaft 5 by means of belt 6 and pulleys 7, 8. This shaft, drives a worm 9, being connected to the worm shaft 75 by a chain and sprocket gearing 10. The worm operates a worm wheel 11 which carries pinion 12 meshing with an annulus 14 secured to the table and by which the table is rotated.

100 The shaft 4 carries at its end near, but beyond, the center of the machine opposite the worm 9 a sprocket 16 which drives a chain 17 which, in turn, drives a sprocket 18 secured to the shaft 19 which projects outwardly to the side of the machine opposite the pulleys 7 and 8. This shaft 19, in turn, carries a worm 20 meshing with worm wheel 20' secured to the upright shaft 21, on which is mounted a cam 22. This cam, as shown, is provided with a depending peripheral flange 24 which is engaged on both sides by rollers 25, which rollers are carried at the outer swinging end of an arm 26 secured to an upright composite shaft 27, to be further described, to which is also secured the nozzle arm 28. Both the lower portion of the shaft 27 and the arm 28, in the preferred form of the invention shown, are hollow, serving as pipes to lead compressed air to the nozzles. This nozzle arm is supported intermediately by a roller 280 on the arm engaging a track 281 and it carries at its outer end a group of sand blast nozzles 30, to be more specifically described.

105 These nozzles, and the arm 28 carrying them, see particularly Figure 2, are oscillated by the cam 22 and lever 26 described, swinging with a slow reciprocating motion on an arc, the cord of which is substantially in line with the radius of the table, the path of the nozzles being toward and from the center of the table and overlying the table.

110 In accordance with the operation of the sand blast table described in my prior Patent No. 1,713,965, the castings are placed on the exposed portion of the table, indicated by reference character 31, and carried through a stationary enclosure or covered portion 32 which contains the nozzles 30, the chamber being elongated in the direction of the circumference to provide for the removal of the abrasive from the work and the dropping of the same through the table, which is in the

form of a grid as shown, before the castings are returned to the exposed portion 31, from which they are removed.

The oscillation of the nozzles, as described, is intended to cause the nozzles to cover a sufficient area and to provide sufficient change of position and direction to cause the work to be treated with a fair degree of uniformity on all sides and as to all exposed surfaces, however, as pointed out in the preamble, the stream of abrasive from each nozzle is substantially conical and particularly where the work is high and projects upwardly to a point relatively near the nozzles the conical streams from the nozzles are intersected where the diameter of said streams is comparatively small so that they are inclined to form paths, i. e., narrow and elongated areas or channels on the surface of the work which are excessively abraded, other portions being cleaned or abraded to a less degree than is intended.

To avoid this effect and to equalize the abrasive action even at the points well above the table where the nozzles are located, it being understood that the nozzles are, in accordance with the prevailing practice, spaced well up from the table and directed downwardly, an additional or secondary motion, the oscillations described being referred to as the primary motion, has been imparted to the nozzles, the secondary motion being referred to in the trade as a "wiggle", consists, in accordance with the preferred form illustrated, in a limited oscillatory or vibratory motion of the nozzles which is most conveniently a substantially arcuate motion about the end of the nozzle arm 28, this being the most convenient central point, as it is the point from which the pipes leading to the nozzles can most conveniently radiate.

In accordance with the form of the machine illustrated, the group of nozzles 30 consists of four nozzles supported on any suitable frame 35, see Figures 2, 4 and 7. In the form of the invention shown, this frame is square, as seen in plan, carrying one of the nozzles 30 at each corner. It consists of four radiating arms 36, 37, 38, 39, the arms 36, 38 and 37, 39, being shown as forming the diagonals of the square frame, the respective radiating arms or members 36 to 39 meeting at the center and each of said radial arms 36, 37, 38, 39 is formed of an upper and a lower member 40 and 41.

The members 40 and 41 of each arm 36, 37, 38 and 39 are in the same vertical plane and are spaced apart vertically at the center of the machine and converge toward their ends at the corners of the frame where they support the nozzles and the ends of the flexible radiating nozzle pipes 42 to which the nozzles 30 are connected, each said nozzle, in the form of the invention shown, being turned downwardly and inwardly toward the center of the group of nozzles. The

braces or frame members 40 and 41 forming the arms 36, 37, 38, 39 are connected at the center, the top members 40 to a collar 43 and the lower members 41 to a collar 44, each of said collars being formed with a bearing 45 at the center, shown in the form of a ball bearing, and each said bearing has its inner member secured to a trunnion 46 at the bottom and 47 at the top, the trunnions being vertical and in alignment and each being secured to the fittings 48.

In the form of the invention shown, the bottom journal 46 is formed on the end of a pin 49 which is seated at its upper end in a vertical bore 50 in the fitting 48, being adjustably secured in said bore by means of set screws 51 or in any suitable manner.

The bearing 45 and the collar 44 are supported on the end of the trunnion 46 by means of a washer or disk 52 and a nut 53 on a threaded reduced extension 54 of the stud 49 on which the shoulder carrying the inner bearing member is formed.

At the top the journal 47 is in the form of a stud suitably shouldered and threaded at its lower end to enter and engage the upper end of the member 48. In the form of the invention shown, the pipes 42 are flexible hose and the oscillation of the frame 35 relatively to arm 28 is taken up by the flexibility of these members. The corners of the frame carrying the nozzles are connected by tension bands 61 forming the sides of the square frame and secured at their ends to the nozzle supports 62, one for each nozzle, through which the shanks of the nozzles are passed and by which they are supported.

The end member or fitting 48 of the nozzle arm 28 is in the form of an elbow, having a horizontal arm with a passage 63 secured to the end of the arm 28 by flanges 64 on both members connected by bolts 65. This portion 63 is in alignment with the main portion 28 of the arm. The member 48 also includes a vertical downwardly extending passage 66 at right angles to the portion 63 and at the lower end of the depending passage 66 are four laterally radiating passages 67. Flanged nipples 68 are secured to the member 48 at the ends of these passages 67 in any suitable manner, as by means of bolts 69. The respective nozzle pipes 42, shown in the form of pieces of rubber hose or other flexible tubing, are secured to the nipples 68 in any suitable manner as by means of hose clamps 70.

The nozzles 30 are also provided with nipple-like extensions 71 to which the flexible pipes or hose 42 are connected by means of clamps or bands 72.

The vibratory motion, wiggling or oscillation of the nozzles 30 relatively to the arm 28 is accomplished by oscillating the frame 35, carrying the nozzles 30 upon the bearings 45, which bearings are carried by the end

member or end fitting 48 of the nozzle arm 28. The flexible pipes 42 provide for and permit their oscillation. This oscillatory motion of the frame 35 is, in the form of the invention shown, communicated thereto by way of connecting members 74 shown as parallel to the arm 28. These are preferably in the form of tension members located on each side of arm 28 and connected to the nozzle frame 35 on each side of the center. In accordance with the construction of applicant's machine, these members 74 have been made of rubber hose and they are connected to the frame by means of hose clamps 73 supported on the frame 35 on each side of its center by means of straps 76 substantially parallel to the nozzle arm 28 and secured at each end to the adjacent fore and aft frame members 36, 37, 38, 39, on each side. As shown, they are suspended from the upper rods 40 of each said member 37, 38, 39, 36 by means of depending brackets 77, see Figure 7.

The hose clamps 73 are accurately located in the direction of the radii of the frame by means of transverse rods 77' which, as shown, are threaded at their ends and seated at their inner ends in correspondingly threaded holes in the member 48 on the respective sides thereof and being threaded at their outer ends through the strips 76 and into the respective hose clamps 73. The rods 77 are held in position in the casting 48 by lock nuts 78.

The connecting rods or flexible tension members are secured at their ends opposite to the clamps 73 to a horizontally rocking arm 75 like a whiffletree, which is pivotally mounted at its center, see Figure 13, beneath the nozzle arm 28 at a point spaced inwardly from the frame 35 toward the center or shaft 27, about which the arm rocks. This arm is shown in Figure 13 with the hose clamps 76', to which the members 74 are secured at the ends of the arm partially removed. These hose clamps are mounted on the opposite ends of the arm 75 in any suitable manner and are turned parallel to the nozzle arm 28. As shown in Figure 13, the clamps 76', portions of which are broken away, are secured to the up-turned ends 77' of the arm 75.

To support the arm 75 at the center, as described, the nozzle arm 28 is provided with a split collar 79 encircling the arm, the bottom half 80 of this collar carrying a bearing 81 for the center of the arm 75 about which the arm swings substantially in a horizontal plane, the details of the bearing not being material to the present invention. As shown, a ball bearing is employed.

The inner bearing ring 82 of said bearing engages a stud 83, the upper end of which is seated in the lower half 80 of the collar and the outer bearing ring 83 is seated in a cup 84, the reduced shank 85 of which extends upwardly through the arm 75, the shank 85 fitting loosely about the stud 83. The cup 84

is further provided with a removable bottom cap 86 which is apertured to pass the reduced end 87 of the stud 83 which extends downwardly through a U shaped depending member 88 formed on the lower half 80 of the collar 79, the extreme lower end of the stud being threaded and provided with a nut 89. The bottom bar 90 of the U is preferably made removable, as shown in side elevation in Figure 2.

To vibrate or wiggle the nozzles 30, the arm 75 is oscillated or vibrated. This is accomplished, in the preferred form of the invention shown particularly in Figures 3 and 5, by means of an electric motor 92.

The motor 92 is, in the form of the invention shown in said figures, provided with a motor shaft 93 on which is mounted a toothed gear 94 which meshes with a toothed gear 95 on the worm shaft 96, which worm shaft carries a worm 97 engaging a worm wheel 98, see particularly Figures 3 and 5, which worm wheel 98 is mounted on and secured to a depending shaft 99, which shaft, see Figures 3 and 5, is provided at its lower end with an eccentric pin 100. The worm gear 97, 98, is enclosed in a casing 144 having a cover plate or gland 145 through which the end of the shaft 99 protrudes.

The depending eccentric pin 100 operates in a slot 101 extending in the direction of the length of a lever arm 102 pivotally mounted at 103 on the bracket 27', which connects the upper end 13 and the lower hollow portion of the shaft 27 in alignment to oscillate together 100 and supports the nozzle arm 28. The lever arm 102, in the form of the invention shown, extends outwardly beyond the slot 101 and is curved backwardly, i. e., to the right in Figure 5, being formed at its extreme swinging 105 end with a horizontally swinging pivot connection comprising a vertical pin 104, to which is secured one end of connecting rod 105, the rod being connected at its opposite end to the swinging arm 75 by means of a 110 block 106' adjustably secured to the arm by bolt 107' seated in an opening 107 in the arm 75, the rod 105 being pivotally connected to the block 106' by pin 106 and there being preferably a series of said openings whereby 115 the radius of the pin 106 about the bearing 81 may be adjusted, changing the relation of the swing of the arm 75 to and with the swing of the arm 102 and correspondingly varying the extent of the vibration of the nozzles.

Figures 9, 10 and 11 show in detail the eccentric pin 100 at the lower end of the shaft 99, which eccentric pin is provided with a roller or rollers 108 supported on the pin by a ball bearing 109 and the slot 101 is shown as formed in a block 110 secured to the lever arm 102.

Referring now to Figure 3, it will be noted that the shaft 27, the lower portion of which is hollow providing a passage 23 which serves

- to lead the abrasive stream to the nozzle arm 28, is formed with a bracket 27' intermediate of its length, which bracket supports an upper section to the shaft at 13 in alignment with the remainder of the shaft and that this upper section carries the cam arm 26 which oscillates the shaft 27 and the arm 28. The bracket 27' also carries a collar 114 which supports the arm 28 and the motor 92 is carried on a plate 112 secured to the upper end portion 13 of the shaft 27, so that the motor 92 and all the parts operated thereby oscillate with the arm 28 and the shaft 27 about the center of the latter shaft.
- Figure 12 is a plan corresponding to Figure 5 showing a modified form of the invention in which the wiggler motion is operated from the same source of power which operates the sand blast table instead of by a separate motor supported on the nozzle arm or nozzle arm shaft. This form of mechanical drive comprises a shaft 120 which is driven by a belt 121 and pulleys 122 and 123 or in any suitable manner, the pulley 123 being mounted on a continuously rotating shaft 124 corresponding to the shaft 4 in Figure 1 and driven in the same or any suitable manner from the source of power which rotates the table. This shaft 124 is also provided, in accordance with the illustration, with pulleys 125 which drive a belt 126 engaging and driving pulleys 127 on the shaft 19, which operates the cam 24 by way of the worm 20 and worm gear 20'.
- The shaft 120 carries at its extreme end remote from the pulleys 122 a bevel gear 129 which meshes with and drives a bevel pinion, 130 mounted on a suitable bracket and carrying a sprocket 131 which drives a chain 132 which, in turn, engages and drives a sprocket 133 rotatably mounted on a bracket 134 corresponding to the bracket 27'. The sprocket 133 is secured to a shaft 136 which carries an eccentric pin 137 operating in a slot 138 in a lever 139, which corresponds to and closely resembles the lever 102 in the previous structure, which lever operates a connecting rod 105, as in the previous construction, the connecting rod being connected to a rocking arm 75 similar to that already described.
- Figure 6 illustrates diagrammatically a single nozzle 30 in central position and shows in dotted lines at 30' the extreme positions of the same nozzle on both sides of the central position. The figure also includes a diagrammatic illustration of the conical stream or blast 140 of abrasive projected from the nozzle and the extreme positions of said stream at 140' on both sides of the central position.
- The operation of the machine is believed to have been fully described in connection with the description of the details of the machine. It will, however, be reviewed in a general way.
- 65 A stream of abrasive is supplied in any suitable manner to the hollow portion 23 of the upright pipe 27 and is led thereby through the fitting 141 enclosed within the bracket 27' located intermediately of the pipe or upright 27, from which fitting it is delivered to the 70 nozzle arm 28. This arm is shown as a pipe, though a passage for the abrasive stream along the arm may be provided in any suitable manner.
- The nozzle arm 28 is oscillated slowly and 75 continuously by means of the cam arm 26 at its upper end engaging the cam surfaces 24 by means of rollers 25 on the arm. The arm 28 and the bracket 27' with the upright shaft or pipe 27 carry all of the moving parts which 80 constitute the wiggler motion and in this connection it will be noted that the shaft 99 is provided with bearings 135 supported on a secondary bracket 143 carried by said bracket 27' at the left in Figure 3, rotating in bearings 13' and 13'', the latter shown fragmentarily and both supported on the machine frame.
- The nozzle arm 28 carries the nozzle frame 35 at its extreme outer swinging end, the 90 frame being mounted on the end of the nozzle arm to oscillate freely relatively thereto. The flexible pipes 42 which feed the nozzles from the fitting 48 at the end of the arm 28 provide for or permit the oscillation of the 95 frame and nozzles, which is transmitted to the frame by way of flexible connections 74 from the rocking arm 75 operated through connecting rod 105 from the swinging arm 100, which is, in turn, operated by the eccentric pin 100 at the bottom end of the shaft 99, already referred to as having bearings on the oscillating bracket 27' and driven through suitable gearing 94, 95, 96, 97, 98, from the motor 92, also supported on the oscillating 105 construction, particularly on the upper end of the shaft 27. Thus a secondary vibratory oscillating motion is imparted to the nozzles in addition to the slow primary pendulum-like motion imparted to the nozzle arm 28 by the cam arm 26 and cam surfaces 24. In this way the tendency to irregular action of the abrasive stream forming paths, particularly on the high work, portions of which approach closely to the nozzles, is completely 110 eliminated and the nozzles thus operated effect, on the contrary, a uniform distribution of the projected abrasive.
- I have thus described specifically and in detail a machine embodying the preferred and a modified form of my invention in order that the nature and the manner of using and applying the same may be fully understood, however the specific terms herein are used descriptively rather than in a limiting sense, the scope of the invention being defined in the claims.
- What I claim as new and desire to secure by Letters Patent is:
1. The combination with a sand blast car-

- rier and means for operating the same to carry the work through the sand blast area and a nozzle of a nozzle arm mounted to oscillate transversely to the motion of the carrier and in a plane substantially parallel thereto, and in a plane substantially parallel thereto, means for oscillating the arm imparting a slow laterally swinging motion thereto, a support carrying said nozzle said support being pivotally mounted on the swinging end of the arm the axis of the pivot being substantially at right angles to the plane of oscillation of said arm, a rocking arm mounted on the nozzle arm and spaced inwardly from the support, flexible means connecting the rocking arm to the support to oscillate the latter, rotary means oscillating with the arm and rotating relatively thereto, an eccentric member carried by said rotary means, a swinging lever oscillated thereby and a connecting rod connecting said rocking arm to said swinging lever.
2. The combination with a sand blast table of a nozzle arm, means for oscillating the arm laterally of the table, a nozzle and means carrying the same and mounted to oscillate relatively to the arm about an axis substantially at right angles to the plane of oscillation of the arm, a prime mover oscillating with the arm and means including an adjustable lever connecting the same to the nozzle carrying means to oscillate the same imparting a secondary motion to the nozzle.
3. In a sand blast apparatus having means for moving articles to be treated through the blasting zone, a plurality of converging nozzles spaced apart, means for moving the nozzles by a slow motion transversely to the direction of motion of the work, means for oscillating the nozzles about an axis which is substantially parallel to the general direction of the nozzles and which is substantially at right angles to the motion of the work and the transverse motion of the nozzles.
4. In a sand blast machine having means for moving the work through the blasting zone, a nozzle arm mounted to reciprocate transversely to the direction of motion of the work and in a plane substantially parallel to the path of the work, means for reciprocating the arm as aforesaid, a plurality of nozzles pivotally mounted in converging relation on the arm to oscillate together relatively to said support and in a plane substantially parallel to the motion of the support and of the work, and means for oscillating the nozzle relatively to the support as aforesaid.
5. In a sand blast machine having means for moving the work through the blasting zone, a nozzle arm mounted to oscillate transversely to the direction of motion of the work, means for oscillating the arm as aforesaid, a plurality of nozzles in angular relation to each other and a support therefor pivotally mounted on the arm to oscillate relatively to said arm and in a plane substantially parallel to the plane of oscillation of the arm and means for oscillating the support relatively to the arm as aforesaid, said oscillating means comprising a centrally pivoted rocking lever carried by the arm, flexible means connecting the ends of said lever to said support, a rotary member oscillating with the arm and means connecting said rotary member to the rocking lever to oscillate the same.
6. In a sand blast apparatus a carrier for the work and means for moving the same, a nozzle arm pivoted to swing transversely to the motion of the work, means for swinging the arm with a slow motion about said pivot, a nozzle support near the end of the arm and a nozzle on said support, the support being pivotally mounted on the arm to swing about an axis disposed in the same general direction as the axis of the arm, and means for imparting a vibratory oscillation to the nozzle support about its axis and relatively to the arm, the nozzle being disposed in substantially the direction of the axis of its support.
7. In a sand blast apparatus a carrier for the work and means for moving the carrier, a nozzle arm pivoted to swing transversely to the motion of the carrier and in a plane parallel to its motion, means for swinging the arm with a slow motion about said pivot, a nozzle support near the end of the arm and a nozzle on said support, the support being pivotally mounted on the arm to swing about an axis substantially parallel to the axis of the arm, and means for imparting a vibratory oscillation of the nozzle about said axis and relatively to the arm, said vibrating means comprising two flexible tension members spaced apart and secured at one end to the support, a pivotally mounted cross arm to which they are connected at their opposite ends, a connecting rod connected at one end to said cross arm and means mounted on the swinging arm near its axis for vibrating the connecting rod in the direction of its length.
8. In a sand blast machine a work carrier and a nozzle carrier mounted to reciprocate transversely to the path of the work carrier, a support and a plurality of nozzles on said support, the support being mounted on the carrier to oscillate relatively thereto, the nozzles converging in the direction of the axis of oscillation of the support, means for reciprocating the nozzle carrier and means for vibrating the nozzle support relatively to the nozzle carrier with a rapid oscillatory motion.
9. In a sand blast machine a nozzle carrier and a work carrier, means for moving the work carrier, and means for moving the nozzle carrier transversely to the work carrier, a nozzle, a support for the same, said support being pivotally mounted on the nozzle carrier, the nozzle being disposed in the

general direction of the axis of the support, and means for vibrating the nozzle support with an oscillatory motion about said axis.

10. In a sand blast machine a nozzle carrier and a work carrier, means for moving the work carrier, and means for moving the nozzle carrier transversely to the work carrier, a nozzle, a support for the same, said support being pivotally mounted on the nozzle carrier, the nozzle being disposed in the general direction of the axis of the support, and means for vibrating the nozzle support with an oscillatory motion about said axis, said oscillating means comprising a motor 15 mounted on the nozzle carrier and a connecting rod connecting the motor to said oscillating support.

Signed by me at Hagerstown, Maryland,
this 10th day of August, 1928.

FOSTER J. HULL.
